UNITED STATES PATENT OFFICE.

JOSEPH H. HAVILAND, OF JACKSON, MICHIGAN.

CORSET-CLASP.

SPECIFICATION forming part of Letters Patent No. 352,820, dated November 16, 1886.

Application filed July 17, 1886. Serial No. 208,266. (No model.)

To all whom it may concern:

Be it known that I, JOSEPH H. HAVILAND, a citizen of the United States, and a resident of Jackson, in the county of Jackson and State 5 of Michigan, have invented certain new and useful Improvements in Corset-Clasps; and I do hereby declare that the following is a full, clear, and exact description of the invention, which will enable others skilled in the art 10 to which it appertains to make and use the same, reference being had to the accompanying drawings, which form a part of this specification, and in which—

Figure 1 is a view of as much of a corset as 15 will illustrate the application of my improved clasp. Fig. 2 is a transverse sectional view of the same taken through a clasp. Fig. 3 is a view of the steel blade having the clasps secured to it; and Fig. 4 is a view of one of the 20 clasps.

Similar letters of reference indicate corresponding parts in all the figures.

My invention has relation to clasps or clamps for corsets; and it consists in the im- 25 proved construction and combination of parts of a clamp or clasp consisting of a bent metallic lip, which may clamp and hold by friction the covered steel of the opposite edge of the corset, as hereinafter more fully described 30 and claimed.

In the accompanying drawings, the letter A indicates the steel blade, to which the clamps or clasps B are secured, and C is the steel blade at the opposite edge of the corset. 35 These blades are covered by the fabric D, with which the entire corset is covered, the said fabric being folded over the steel, having the clasps in a backwardly-doubled fold, E, folded upon the outside of the corset, while the plain 40 steel blade is inclosed in a backwardly-doubled fold, F, folded upon the inner side of the corset.

The clamps or clasps consist each of a lip or plate, G, having its outer end curved slightly 45 outward, as shown at H, and of three prongs, I, I', and J, formed by two cuts from the end of the plate from which the clasp is formed.

The steel blade is formed with longitudinal slots K, of the same length as the width of

the central prong of the clasp, and the cen- 50 tral lip of each clasp is inserted through these slots and bent outward upon the inner side of the steel blade, and the two outer prongs of the clasps are folded over the inner edge of the steel blade, the lip or plate of the clasp 55 being bent slightly out of the plane of these outer prongs and inserted through a slot, L, in the covering of the blade, the lips of the clasps being bent sufficiently out of the plane of the prongs to admit of the covered steel 60 blade of the other edge of the corset to be inserted under the lips, so as to be firmly clamped between the lips and the blade. It will thus be seen that the edges of the cor- 65 set will be held together by the frictional re- sistance between the lips and covered steel blade having the clasps and the covered plain steel blade, the clasps thus providing a sim- 70 ple fastening for the corset, which will hold the edges together with sufficient strength to prevent them from becoming disengaged dur- 75 ing ordinary use, while the edges may very easily be fastened and again unfastened, it being only necessary to force the edge of the plain covered blade under the lips of the clasps, when the edges are fastened, while for unfastening the edges, the plain blade is drawn out from under the lips.

The clasps may be very easily secured to the slotted blade by simply inserting the cen- 80 tral prong in the slot, and thereupon bending the outer halves of the outer prongs around the edge of the steel blade, when the clasp is se- cured, and may have its lip inserted through the slot in the covering. 85

Having thus described my invention, I claim and desire to secure by Letters Patent of the United States—

1. The herein-described corset-clasp, con- 90 sisting of a plate having a curved lip, H, at one end and three hook-shaped prongs at the other end, the middle prong, J, being doubled back upon the plate so as to leave an open- 95 ing or recess between the two outer prongs, and having also a shoulder or offset at the point where the plate is slotted to form the prongs, substantially as and for the purpose shown and set forth.

2. The combination, with the slotted steel blade A, of the clasp-plates B, provided with the curved lip H, and prongs I, J, and I', constructed as described, and having an offset or 5 shoulder between said prongs and the curved lip, substantially as and for the purpose shown and specified.

In testimony that I claim the foregoing as my own I have hereunto affixed my signature in presence of two witnesses.

JOSEPH H. HAVILAND.
